MAGNETO UNIT

Wilbur L. Carlson, Rochester, N. Y., assignor to
 General Motors Corporation, Detroit, Mich., a
 corporation of Delaware

Application August 7, 1941, Serial No 405,743

13 Claims. (Cl. 171—209)

This invention relates generally to the construction of magneto units and more particularly to certain features of construction which are of general use but especially desirable for use in units for airplane engine ignition.

Considerable trouble has been encountered since the advent of relatively high altitude flying with magneto units which may operate satisfactorily at low altitudes but which either fail or operate erratically at high altitudes.

It has been found that one of the principal reasons for magneto failures and improper operation at high altitudes is due to the fact that as the density of the atmosphere decreases as an airplane ascends the dielectric strength of the rarefied atmosphere decreases to such an extent that the ignition spark in the distributor of the magneto unit which should jump successively from the rotary distributor arm to the spaced distributor points or electrodes will flash or arc over the gaps between several of the distributor points simultaneously and thus cause improper firing of the engine cylinders.

One of the objects of this invention is to overcome this defect in prior units by providing a unit construction in which the distributor is located within a separate chamber which is entirely sealed against the entrance of external air so that the proper spark distribution to the cylinders is not affected by changes in atmospheric conditions or changes in altitude.

A further object is to provide in such a construction a sealing means for the rotary drive connection to the distributor arm in which the efficiency of the seal increases with decrease in density of the atmosphere at higher altitudes to prevent leakage and thereby maintain the distributor chamber substantially at the atmospheric pressure of lower altitudes or ground level.

As will be described more fully hereinafter it is also contemplated that the sealed distributor chamber may, if desired, be maintained above the atmospheric pressure at ground level and charged with some medium other than air such as an inert gas to reduce the extent of corrosion of the distributor points and increase the breakdown voltage.

In addition to improper cylinder firing at relatively high altitudes there have been instances where the ignition has failed completely because of electrical breakdown and undesired grounding of the current conducting means extending from the high tension coil terminal to the distributor arm.

A further object of the present invention is to provide a construction affording a more completely insulated path for the high tension current with a proper spacing of those parts of the magneto unit that are of widely varying potential.

Other objects and advantages of the present invention will be apparent from the following description of the embodiment illustrated in the accompanying drawing, in which:

Fig. 1 is a side elevation of the complete magneto unit with parts broken away and parts in vertical section.

Fig. 2 is a fragmentary front elevation of the unit of Fig. 1 on a slightly reduced scale.

Fig. 3 is a fragmentary vertical section of the sealing means on a slightly enlarged scale.

Referring first to the showing in Fig. 1, only those parts essential to an understanding of the features of construction of the present invention have been illustrated in detail and those parts not so illustrated may be of any desired conventional construction.

It will be understood, for instance, that the portion of the casing indicated at 4 is adapted to house a generator with the usual stator and a rotor having a shaft 6 with one end thereof projecting outside the casing and adapted to be connected to and driven by the engine. The stator includes vertically extending spaced poles 8 which engage the opposite ends of the core of the induction coil 10 having primary and secondary windings. The primary windings are periodically opened by an interrupter mechanism which may be located within the portion of the casing indicated at 12 and operated by an extension of the rotor shaft and the secondary windings furnish the high tension ignition current which is supplied to the engine through the distributor mechanism to be hereinafter described.

In accordance with the present invention the distributor per se is located within a completely sealed and insulated chamber indicated generally at 14 which is formed primarily by the parts 16 and 18 of molded insulation material such as Bakelite. The spaced distributor points or electrodes 20 may consist of metal inserts in the molded part 16 with such points arranged, if desired, as shown in two parallel arcuate rows in the upper half of the distributor chamber with bores 22 to receive the separate conductors leading to the respective spark plugs of the engine. The other molded part 18 is adapted to close one end of part 16 and is shown as having molded therein a metal insert 24 with a bore 26 to re-

ceive a conductor providing for the use of a booster magneto or other external current source, if desired, as auxiliary ignition for starting purposes.

Considering now the rotating parts of the distributor mechanism, a rotor 28 has been shown with a distributor arm 30 cooperating with one row of distributor points 20 and a distributor arm 32 cooperating with the other row of distributor points 20. As will be more fully described hereinafter, arm 30 is connected to the high tension winding or coil to furnish the primary ignition current and arm 32 may be connected to the booster magneto or external current source for starting.

It should be understood that in accordance with known practice wherein the distributor points are arranged in parallel arcuate rows, arms similar to 30 and 32 but cooperating with adjacent rows of distributor points are located on the distributor rotor 28 diametrically opposite the arms shown in Fig. 1 and the respective pairs of arms 30 and 32 may be slightly angularly spaced to provide a retarded spark for starting. Since this known arrangement constitutes no part of the present invention it is not considered necessary to provide any further disclosure thereof but it should be noted that the showing in Fig. 1 is not a true vertical section through the distributor rotor 28 insofar as the relative angular location of arms 30 and 32 is concerned.

The distributor rotor 28 is shown as being formed of molded insulation material with the distributor arm 32 consisting of a metal insert therein, and with the distributor arm 30 riveted to a metal bearing housing 34 and also constituting metal inserts in the rotor. The arm 32 is connected by means such as bolt 36 to a metal strap 38 on the molded insulating member 40 which is secured to the rotor 28 by such bolt. The strap 38 extends to the axis of rotation of the distributor rotor and is located at this point sufficiently close to the metal insert 24 to provide for the transmission of the booster ignition current to the distributor arm 32.

The bearing housing 34 is secured to the inner end of a drive shaft 42 which extends from this connection to the distributor rotor through a sleeve 44 which is preferably molded as an insert in the part 16 and extends on both sides of the wall of this part opposite the part 18. The outer end of shaft 42 is enlarged as at 46 to provide for the connection thereof to the drive gear 48 and to receive the shaft sealing means to be hereinafter described. The gear 48 which is formed of suitable insulating material meshes with a gear 50 of similar material which is mounted on the magneto rotor shaft 6. A metal bearing housing 52 is molded as an insert in gear 48 and this bearing housing 52 and the bearing housing 34 in distributor rotor 28 receive the outer races of the spaced antifriction bearings 54 with the inner races thereof mounted adjacent the ends of the stationary sleeve 44.

The outer end of shaft 42 is formed with an axially extending recess to receive a spring pressed contact member 56 which is adapted to contact with the terminal 58 of the high tension winding of coil 10 to conduct the high tension ignition current to the distributor arm 30.

The shaft sealing means which is indicated generally at 60 in Fig. 1 and shown in detail in Fig. 3 functions to prevent the entrance of air to the distributor chamber through the space which would otherwise exist between the outer

end of shaft 42 and sleeve 44. The outer end of the sleeve 44 is provided with the stationary seal ring 62 which is adapted to be engaged by the rotating seal ring 64 secured by a sleeve 66 to a laminated flexible diaphragm 68.

The outer edge of this diaphragm 68 is secured within the bearing housing 52 between a flange 69 on such housing and the enlargement 46 on shaft 42 with the outer bearing race 70 and a member 72 functioning as spacers between the diaphragm and the flange on the bearing housing. A securing means such as the externally threaded nut 74 is provided to both clamp the diaphragm 68 between member 72 and shaft enlargement 46 and to secure the gear 48 non-rotatably to the shaft 42. As shown in Fig. 3, the nut 74 is threaded within the outer end of the bearing housing 52 with a key 76 interlocking between a recess in the outer face of shaft enlargement 46 and a notch 78 in housing 52 and with a washer 80 having a bent lug 82 to engage in an opening in key 76 and also having a portion 84 which may be bent within the nut 74 to prevent relative rotation of the latter after assembly.

The engaging surfaces of the seal rings 62 and 64 are highly finished and the ring 64 is maintained in sealing contact with the ring 62 by the spring 86 which may assume any form but is illustrated as a thin disk of spring metal having fingers or prongs bent out therefrom.

With reference to the foregoing description, it will now be apparent that a completely insulated and sealed chamber has been provided for the distributor with a sealing means for the distributor drive shaft which extends outside of the chamber. In stating the objects of the present invention it was mentioned that the sealing means is so constructed and arranged that the efficiency of the seal increases with decrease in density of the atmosphere at higher altitudes. This desirable result is obtained since on reference to the showing in Fig. 1, it will be seen that the space within the distributor chamber 45 is in communication through the clearance between shaft 42 and sleeve 44 with the side of the seal diaphragm 68 on which the spring 86 is located so that any pressure of the air or gas to be referred to hereinafter in the distributor 50 chamber is operative in the same direction as spring 86 to force the seal ring 64 against the seal ring 62. Even though the pressure within the chamber may be only substantially atmospheric pressure at ground level it will therefore 55 be apparent that at relatively high altitudes when the external air pressure decreases the resulting differential in pressures within and outside the distributor chamber which are effective on opposite sides of the seal diaphragm will cause 60 an increased pressure contact of the sealing surfaces of the seal rings 62 and 64.

It was also mentioned in stating the objects of the present invention that the sealed distributor chamber may, if desired, be maintained above the 65 atmospheric pressure at ground level and also charged with some medium other than air such as an inert gas. Since it is obvious that there are many structural ways in which air under pressure or an inert gas may be introduced into the distributor chamber, one arrangement of parts of this purpose has only been diagrammatically illustrated in Fig. 2, in which valve outlines have been indicated as at 88 as located in opposite sides of a cover 90 forming a part of the outside casing 70 which are adapted to communicate through pas-

sages such as 92 and 94 in the molded part 18 with the interior of the distributor chamber 14. To prevent any leakage adjacent the valves it is apparent that the valve casings could, if desired, be molded as inserts in the part 18 and extend outwardly through the cover 88 or terminate within the cover and be accessible on removal thereof.

The details of construction of the valves may conform to any standard valve and are not essential to an understanding of the present invention, and in fact, ordinary stop cocks may even be employed instead of valves. If, however, air or gas under pressure is to be maintained within the distributor chamber one of the valves could be in the form of a pressure relief or regulating valve. If it is desired to charge the chamber with an inert gas such as carbon dioxide (CO₂) which has been found to be a very satisfactory medium, the gas would be introduced under pressure through one valve while the other valve would be opened or so constructed as to function as a bleed outlet opening to ensure that all air is cleared from the chamber. Such valve or bleed opening would of course be closed as soon as the chamber is filled with gas.

It is also contemplated, although not shown in the drawing, that a source of air or gas under pressure such as a small bottle or container of compressed air or gas could be associated, if desired, with the distributor chamber to take care of any minor leakage of air or gas from the chamber.

With reference to the current conducting means extending from the high tension coil terminal to the distributor arm, it should be noted that the path of high tension current is primarily through the distributor drive shaft. Although such a general arrangement is known in the prior art, it has heretofore been the practice to either construct the shaft of insulating material around a central current conducting rod or insulate the shaft from its bearings and other adjacent parts, and there have been many failures of this insulation.

As appears in Fig. 1, no attempt is made to insulate the shaft 42 from the bearings 54 or adjacent metal parts such as sleeve 44 but the construction is such that high tension current may be carried and be present in all of the metal parts adjacent to the shaft 42. Since gear 48 and parts 16 and 18 of the distributor chamber are constituted by molded insulation material it will be apparent that in the construction disclosed herein there is no metal part or point at ground potential close to any part of the high tension circuit, and therefore the chance of electrical breakdown is considerably reduced if not entirely eliminated.

Other features of the present construction together with the advantages thereof will be obvious to those skilled in the art. It will be apparent, for instance, that the sealing means for the distributor drive shaft is located within the bearing housing 52 outside of the distributor housing and that a floating mounting of the distributor shaft 42 in the sleeve 44 is provided by the bearings 54 which are relatively widely spaced by reason of their location adjacent each end of the sleeve.

In certain prior constructions wherein the distributor arms constitute inserts in a distributor rotor of molded insulating material it has been found that such material tends to become unstable and yield or give under the relatively high ambient temperature conditions encountered during operation and it is therefore difficult to maintain the close mechanical tolerances be-

tween the distributor arms and distributor points to provide the proper spark gaps at all times. In the present construction it will be seen that the distributor arms 38 for the primary ignition current are secured, as heretofore described, directly to the metal bearing housing 34 which is in turn secured directly to the distributor shaft 42 so that even though the arms 38 constitute inserts in the molded rotor 28, such arms are so mounted as to prevent any radial displacement thereof.

It should be understood that although but one embodiment of the present invention has been shown and described herein, other embodiments and many modifications may be obvious to those skilled in the art without departing from the spirit or scope of the invention as defined by the claims appended hereto.

I claim:

1. A magneto unit including a current distributing mechanism having a rotatable distributor arm, a separate chamber for said mechanism, a stationary sleeve mounted in and extending through a wall of said chamber, a drive shaft extending through said sleeve and connected to said distributor arm, and a sealing means for said shaft to prevent the entrance of external air to said chamber between said sleeve and shaft, said sealing means including a seal ring carried by said sleeve, a seal ring carried by said shaft and rotating therewith, and means to force said rings into sealing contact engagement.

2. A magneto unit for airplane engine ignition systems including a current distributing mechanism having a rotatable distributor arm, means providing a chamber for said mechanism, a drive shaft extending into said chamber and connected to said distributor arm, and a sealing means for said shaft to prevent the entrance of external air to said chamber, said sealing means including a flexible diaphragm, a non-rotatable seal ring and a rotatable seal ring, one of said seal rings being mounted by means of said flexible diaphragm, resilient means on one side of said diaphragm to force said latter seal ring into surface contact engagement with the other seal ring, said sealing means being so arranged that the said chamber communicates with the side of said diaphragm on which said resilient means is located whereby the pressure of the medium within said chamber will supplement said resilient means on increase in altitude in maintaining the contact engagement between said seal rings.

3. A magneto unit including a coil having a high tension terminal and a current distributing mechanism having a rotatable distributor arm, a chamber for enclosing said mechanism, a stationary sleeve extending through a wall of said chamber, bearings carried by said sleeve, a drive shaft extending through said sleeve and journaled in said bearings and connected to rotate said distributor arm, and means to electrically connect said high tension terminal to said distributor arm including said drive shaft, said sleeve and bearings being uninsulated from said shaft and at the same relative potential as said shaft.

4. A magneto unit including a coil having a high tension terminal and a current distributing mechanism having a distributor rotor of insulating material with a distributor arm, a chamber of insulating material for enclosing said mechanism, a stationary metal sleeve extending through a wall of said chamber, bearings carried by said sleeve, a metal drive shaft extending through said sleeve and provided with a drive gear of

insulating material, means connecting said shaft to said distributor rotor, and means to electrically connect said shaft to said high tension terminal and said distributor arm whereby said sleeve and bearings will be at the same relative potential as said shaft.

5. A current distributing mechanism having a rotatable distributor arm, means providing a chamber for said mechanism, a drive shaft extending through a wall of said chamber and spaced therefrom, said drive shaft having its inner end connected to said distributor arm within said chamber, and a sealing means for said shaft adjacent the outer end of said shaft and outside of said chamber to prevent the entrance of external air to said chamber through the space between said shaft and chamber wall.

6. A magneto unit including a coil having a high tension terminal and a current distributing mechanism having a rotatable distributor arm, a chamber for enclosing said mechanism, a drive shaft extending through a wall of said chamber, said drive shaft having its inner end mechanically and electrically connected to said distributor arm within said chamber and having its outer end electrically connected to said high tension terminal outside of said chamber, and a sealing means for said shaft to prevent the entrance of external air to said chamber.

7. A current distributing mechanism having a rotatable distributor arm, a chamber for said mechanism, a stationary sleeve mounted in and extending through a wall of said chamber, a drive shaft extending through said sleeve and connected to said distributor arm, and a sealing means for said shaft to prevent the entrance of external air to said chamber between said sleeve and shaft, said sealing means including a seal ring carried by the outer end of said sleeve, a seal ring carried by said shaft and rotating therewith, and means to force said rings into sealing contact engagement.

8. A current distributing mechanism having a rotatable distributor arm, a chamber for said mechanism, a stationary sleeve mounted in and extending through a wall of said chamber, a drive shaft extending through said sleeve, said drive shaft having its inner end connected to said distributor arm within said chamber, a drive gear connected to the outer end of said drive shaft outside of said chamber, and spaced bearings between said sleeve and drive shaft, said bearings being located adjacent the inner and outer ends of said sleeve on opposite sides of said chamber wall.

9. A current distributing mechanism having a distributor rotor, a chamber for said mechanism, a stationary sleeve mounted in and extending

through a wall of said chamber, a drive shaft extending through said sleeve, said drive shaft having its inner end connected to said distributor rotor within said chamber, a drive gear connected to the outer end of said drive shaft outside of said chamber, and spaced bearings for mounting said drive shaft in spaced relation to said sleeve, said bearings being located adjacent the inner and outer ends of said sleeve and interposed between said sleeve and distributor rotor and between said sleeve and drive gear.

10. A current distributing mechanism having a rotatable distributor arm, a chamber for said mechanism, a stationary sleeve mounted in and extending through a wall of said chamber, a drive shaft extending through said sleeve, said drive shaft having its inner end connected to said distributor arm within said chamber, a drive gear connected to the outer end of said drive shaft outside of said chamber, and means to mount said drive shaft to rotate within said sleeve including a bearing housing on said gear and an antifriction bearing interposed between said bearing housing and the outer side of said sleeve.

11. A current distributing mechanism having a distributor rotor including a bearing housing, a stationary sleeve, a drive shaft extending through said sleeve, said drive shaft having one end thereof connected to said bearing housing, and means to mount said drive shaft to rotate within said sleeve including an antifriction bearing interposed between said bearing housing and the outer side of said sleeve.

12. A magneto unit including a coil having a high tension terminal and a current distributing mechanism having a distributor rotor including a bearing housing, a stationary sleeve, a drive shaft extending through said sleeve, said drive shaft having one end thereof connected to said bearing housing and the other end thereof electrically connected to said high tension terminal, a distributor arm connected to said bearing housing, and means to mount said drive shaft to rotate within said sleeve including an antifriction bearing interposed between said bearing housing and the outer side of said sleeve.

13. A current distributing mechanism having a rotatable distributor arm, a chamber for enclosing said mechanism including a wall constituted of insulating material having a metal sleeve molded therein and extending transversely through said wall, a drive shaft extending through said sleeve, said drive shaft having the inner end thereof connected to said distributor arm within said chamber, and bearings between said shaft and said sleeve.

WILBUR L. CARLSON.
